UNITED STATES PATENT OFFICE.

SAMUEL S. COLT, OF ORANGE, NEW JERSEY.

DOOR OR WINDOW FRAME.

1,369,620.

Specification of Letters Patent. Patented Feb. 22, 1921.

Application filed February 27, 1918. Serial No. 219,364.

To all whom it may concern:

Be it known that I, SAMUEL S. COLT, a citizen of the United States, residing at Orange, in the county of Essex and State of New Jersey, have invented certain new and useful Improvements in Door or Window Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in concrete construction; and the invention has reference, more particularly, to a novel method and means for providing the concrete walls of buildings and other structures made of concrete, or similar material, with openings for windows or doors, without cutting openings in the cribbing or form-boards, employing in connection with the cribbing or form-boards, at desired points, so as to form parts of the mold or form into which the concrete-mixture, or the like is poured, various members comprising parts of the window or door-frames.

The present invention, therefore, has for its principal object to provide a simple and novel method, as well as a novel and simply-constructed mold-form, comprising in combination with cribbing or form-boards, various members or parts of window or door-frames, for the purpose of providing walls and other structures of concrete, or similar material, with openings, in which the window-frames or door-frames are fixed, when the cribbing or form-boards are removed, the window or door-frames being ready to receive the window-sashes or doors.

The present invention has for its further object to provide a novel construction of frame, and a novel arrangement of the parts thereof, such frame to be disposed between the cribbing or form-boards, and being permanently fixed in the concrete-structure after the cribbing or form-boards are taken down, providing in addition to the frame-structure, a novel drip or means which will prevent the water from dripping or flowing into the window or door-opening.

The invention has for its further object to provide a novel construction of frame to be disposed between the cribbing or form-

boards, said frame being permanently fixed in the concrete-structure after the cribbing or form-boards are taken down, the said frame being provided with an adjustably disposed sill, normally providing a part of the mold-form, but, after the concrete-structure has been built and the cribbing or form-boards have been removed, being adapted to be moved or pushed in an outward direction so as to project beyond the vertical face of the finished wall and thereby providing the projecting sill-portion usual in the constructions of buildings, etc.

Other objects of the present invention not at this time more particularly enumerated will be clearly understood from the following detailed description of the present invention.

With the various objects of the present invention in view, the said invention consists, primarily, in the novel mold-form for providing concrete walls, and the like, with window or door receiving openings, and the novel method of producing the same; and, the invention consists, furthermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:—

Figure 1 is a transverse vertical sectional representation of a mold-form, showing fragmentary portions thereof, that is, oppositely spaced cribbing or form-boards, and the various members or parts of a frame-structure for either a window or door, said frame-structure forming part of the mold, said view also showing in connection therewith, fragmentary portions of the concrete-mixture disposed between the said cribbing or form-boards and about the said frame-structure; and Fig. 2 is a horizontal sectional representation of the same, said section being taken on line 2—2 in said Fig. 1, looking in the direction of the arrow α .

Fig. 3 is a view similar to Fig. 1, showing portions of the finished wall-structure and the various parts of the frame-structure disposed in the wall, ready to receive a window or door.

Fig. 4 is a view similar to said Fig. 1, of

an arrangement of the various parts to provide the concrete wall-structure and a window-frame fixed therein, the window-frame being placed so as to provide in front of the 5 same what is known in the art as a "reveal"; and Fig. 5 is a horizontal sectional representation of the same, said section being taken on line 5—5 in said Fig. 4, looking in the direction of the arrow y.

10 Similar characters of reference are employed in all of the said above described views, to indicate corresponding parts.

Referring now to the several figures of the drawings, the reference-character 1 indicates a plurality of oppositely disposed form-boards, cribbing, or mold-sections, which in the drawings are shown as being vertically placed, but which, as will be evident, may be arranged in any other suitable 15 manner, the opposite boards or sections being suitably spaced according to the thickness of the wall to be produced, and held in their respective positions by means of suitable spacing and retaining means of any desirable construction.

As illustrated in Figs. 1 and 2 of the drawings, each frame-structure to be disposed between the said mold-sections or form-boards 1, at any desired point, com-

30 prises a pair of vertically disposed side-members or uprights 2, to the upper end-portions of which is suitably secured, so as to connect the said upper ends of the said uprights, a horizontally disposed head-jamb 3, and to the lower end-portions of which is suitably secured, so as to connect the said lower ends of the uprights, a horizontally disposed main-sill, as 4. Located in front of the said head-jamb 3, and secured thereto

35 by means of nails 5, or other suitable fastening means, is a horizontally disposed casing-member 6, said member extending in an upward direction above the upper surface of the said head-jamb, and being provided in 40 its rear face with rearwardly extending screws 7, or other rearwardly projecting means, the purpose of which will be self-evident from an inspection of Figs. 1 and 3 of the drawings.

45 Suitably mounted upon the upper surface of the said casing-member 6 is a strip, as 8, upon which is secured, by means of the nails 9 which also secure the strip 8 to the casing-member 6, a plate 10, made of sheet-metal

50 or any other suitable material. The said plate 10 is preferably provided at its rear edge with an upwardly extending flange-like member, as 11, and at its forward edge with a downwardly extending portion, as 12,

55 normally lying against the outer faces of the strip 8 and the casing-member 6, as shown in Fig. 1.

Suitably connected with the under surface-portion of the main-sill 4, by means of 60 screws 13, or other means, is a sub-sill 14,

and in alignment with the said casing-member 6 are a pair of vertically disposed end-members 16, suitably secured at their lower ends, by means of nails 15, or other suitable fastening means, to the said sill 4, so that 70 the various parts just described will provide a frame-like structure in which, at the proper time, may be mounted a window-sash or sashes, or may be hung a door, if desired. Back of the sub-sill 14, and suitably secured 75 by means of nails 17 or other fastening means, to the under surface-portion of the sill 4 which extends beyond the rear surface of said sub-sill, is a block 18 of any suitable length, the purpose of which will presently 80 be more fully described.

Under normal initial conditions, when the frame-structure just described is to be used as a part of the mold, the general arrangement of the various parts is such, that the 85 several oppositely placed cribbing or mold-boards 1 have the frame-structure snugly fitted between them, with the boards 1 extending across the opposite faces of the said frame-like structure and thus closing 90 the openings in the front and rear of said frame-like structure, as clearly shown in said Figs. 1 and 2 of the drawings.

The mold-form having thus been completed, concrete or other similar mixture, as 95 19, is poured into the mold, between the boards 1 thereof and about the frame-structure disposed between the said boards.

When the concrete-mixture or similar material has set sufficiently, thus completing a 100 wall, the cribbing or form-boards 1 are taken down, but the frame-structure for the window-sashes or doors is permitted to remain permanently embedded in the completed wall or other concrete structure 105 produced.

After the removal of said cribbing or form-boards 1, the nails 17 and screws 13 are removed sufficiently, first to permit of the withdrawal of the block 18 for the insertion in the space thus left and back of the sub-sill 14 of a rod or proper tool for pushing the said sub-sill forwardly into the position indicated in Fig. 3 of the drawings, so as to project beyond the outer face of the 110 wall, as shown. This having been accomplished, the screws 13 are once more screwed down, through the sill 4 into the sub-sill 14, so as to fix said sub-sill in its adjusted 115 relation to the wall, as will be clearly evident. The open spaces provided by the forward movement of the sub-sill 14 and the removal of the block 18 may be plugged up with concrete; or, if desired, the said block 120 18 may be reinserted and secured in place 125 by driving the nails 17 back into position as indicated in Fig. 3. The depending portion 12 of the plate 10 is also bent upwardly and then outwardly, to permit of the placing of a drip-strip, as 20, against the ex- 130

posed face of the previously-mentioned strip 8, the portion 12 of the metal plate 10 then being forced down upon the upper surface and against the outer face of the 5 drip-strip 20, the metal drip thus provided and the strip 20 being thereupon secured in their fixed positions by means of nails 21 or other suitable means of fastening.

If desired, a molding, as 22, may then also 10 be secured in position, as shown in said Fig. 2, for ornamental effect.

A window-sash or sashes, or a door, may be then readily mounted in the frame-work, thus permanently located in the wall.

15 Where a "reveal" is desired, as indicated in Fig. 4 of the drawings, the strip 8 is omitted, and the various frame-members 2, 3, 4, 6 and 16 are made of such widths, that a space, as 23, between the inner faces of 20 the one set of cribbing or form-boards 1 and the outer faces of the members 6 and 16 will be provided, this space having disposed therein a space-closing frame, board or boards, as 24, substantially as shown in 25 Figs. 4 and 5 of the drawings.

After having poured the concrete-mixture in this form of mold, the cribbing or form-boards 1 and the frame, board or boards 24 are removed. The sub sill 14 is moved 30 forward and secured in its adjusted position in the manner hereinbefore described, with the result that a window-frame is secured in its permanent position in the wall, and that the frame is located sufficiently back 35 of the front face of the wall, so as to provide what is known in the architectural art as a "reveal."

From the foregoing description of the present invention, it will be seen that I 40 have produced a simple and operative mold-construction, of which a window or door-frame provides a component part, which frame is left in its position in the finished wall, after the cribbing or frame-boards 45 have been taken down, the cribbing or form being easily and quickly erected, and just as quickly knocked down or dismantled when the wall or structure has been completed.

50 I am fully aware that changes may be made in the general arrangements and combinations of the various devices and parts, as well as in the details of the construction of the said parts, without de- 55 parting from the scope of the present invention as set forth in the foregoing

specification and as defined in the clauses of the claims which are appended thereto. Hence, I do not limit my present invention to the exact arrangements and 60 combinations of the several devices and parts as described in the foregoing specification, nor do I confine myself to the exact details of the construction of the said parts, as illustrated in the accompanying drawings. 65

I claim:—

1. In a concrete structure, in combination with the concrete wall thereof, a window-sash or door-receiving frame embedded in said wall, said frame consisting of vertically disposed uprights and a head-jamb mounted upon the upper ends of said uprights, and a sill located between the lower end-portions of said uprights, said sill comprising a main sill-member, a second sill-member movably disposed beneath said main sill-member, a fastening means removably disposed with relation to said sill-members for securing said second-mentioned sill-member in various positions with relation to 80 said main sill-member, and a filler-means removably disposed beneath said main sill-member and back of said second-mentioned sill-member for removal and insertion of a member back of said second mentioned sill-member and to project the latter beyond the outer face of the concrete wall. 85

2. In a concrete structure, in combination with the concrete wall thereof, a window-sash or door-receiving frame embedded in 90 said wall, said frame consisting of vertically disposed uprights and a head-jamb mounted upon the upper ends of said uprights, and a sill located between the lower end-portions of said uprights, said sill comprising a main sill-member, a second sill-member movably disposed beneath said main sill-member, a fastening screw for separably connecting said sill-members, a block 95 removably disposed beneath said main sill-member and back of said second-mentioned sill member, and a nail connecting said block with said main sill-member, substantially as and for the purposes set forth. 100

In testimony, that I claim the invention 105 as set forth above, I have hereunto set my hand this 21st day of February, 1918.

SAMUEL S. COLT.
